UNITED STATES PATENT OFFICE.

JOHN T. NEEDHAM, OF BAYONNE, NEW JERSEY, ASSIGNOR, BY MESNE ASSIGNMENTS, TO THE LAMSON COMPANY, OF NEWARK, NEW JERSEY, A CORPORATION OF NEW JERSEY.

PNEUMATIC-DESPATCH-TUBE APPARATUS.

1,148,116.

Specification of Letters Patent. Patented July 27, 1915.

Application filed June 29, 1910. Serial No. 569,439.

To all whom it may concern:

Be it known that I, JOHN T. NEEDHAM, a subject of the King of Great Britain, a citizen of Canada, and resident of Bayonne, 5 in the county of Hudson, State of New Jersey, have invented certain new and useful Improvements in Pneumatic-Despatch-Tube Apparatus, of which the following is a complete specification.

10 The main object of this invention is to provide a pneumatic despatch tube apparatus wherein a single transmission tube leads from a number of outlying stations to a central station, and provided with a carrier receiving terminal at each of said outlying stations, a plurality of return tubes extending from said central station to the outlying stations. In the operation of such a system, carriers may be placed in the 15 transmission tube through any one of the receiving terminals on the transmission tube, and carried through the tube to the central station. The carriers from the central station are distributed in the outgoing tubes to 20 be returned to their respective stations. In tube systems of this general character heretofore designed and covered by my prior applications for patents, the carriers are drawn through the transmission tube to the central 25 station and forced from the central station to the outlying stations, suitable means being provided to connect the air-pressure pipe to any one of the outgoing transmission tubes. In the present application the 30 carriers are forced through the single transmission tube and are sucked or drawn through the return tubes, the receiving ends of the return tubes being open at all times.

A further object of the invention is to 35 connect the pressure side of the air blower or pump to the single transmission tube and the exhaust side thereof to the return tubes.

Another object of the invention is to provide means whereby the suction side of the 40 blower may be successively connected to each of the return tubes so that air will be drawn first through one of said tubes for a predetermined time, and through another tube and so on throughout the entire series 45 of return tubes.

Other important objects and advantages of the invention will fully hereinafter appear.

In the drawings, Figure 1 is a diagrammatic view of the apparatus; Fig. 1^a a de-

tail vertical sectional view of the receiving end of one of the tubes 10. Fig. 2 an enlarged view of the blower, motor, and the valve operating mechanism; Fig. 3 a vertical sectional view through one of the pneumatic switches of the valve operating means; Fig. 4 a transverse sectional view of the vacuum valve operating means; Fig. 5 a similar view of the pressure actuated valve opening means; Fig. 6 a longitudinal sectional view of one of the valves taken on the line VI—VI of Fig. 5; Fig. 7 a side elevation of one of the terminals in the transmission tube; Fig. 8 a transverse sectional view thereof; and Fig. 9 a vertical sectional view of one of the vacuum delivery terminals at the outlying stations.

Referring to the various parts by numerals, 1 designates the transmission tube which leads from the outlying stations to the central station and is connected at said station with a delivery chute 2 which may be of any suitable construction. The distant end of this transmission tube is connected to the pressure side of a blower 3. 60 This transmission tube is provided at suitable points with carrier receiving terminals 4, each of said terminals consisting of a rotatable sleeve 5 formed with a cut-out portion 6 which is adapted to register with 65 a similar cut-out portion 7 in the transmission tube. It is manifest that by rotating the sleeve in the proper direction the solid portion thereof may be brought in position to cover the opening 7 in the transmission tube. Suitable stops 8 are provided, adapted to be engaged by shoulders 9 on the sleeve to stop the sleeve in position 70 to cover or uncover the cut-out portion 7 of the transmission tube. A terminal closure 95 of this construction will prevent the escape of the air under pressure in the transmission tube, and said air will not tend to open the closure device.

A series of return tubes 10 extend from 80 the central station to a point adjoining each of the receiving terminals 4. These return tubes are open at their central station ends, and are connected to delivery terminals 11 at the outlying stations. These terminals 105 each consists of the delivery pipe 12 arranged to deliver the carriers through the hinged doors 13 and the exhaust pipes 14 which are connected to said heads and arranged to draw air through the tube 10 and 110

the delivery pipe 12. Each of the pipes 14 is connected to the main suction pipe 15 which is connected to the suction side of the blower 3. At the junction of the pipes 14 with the main suction pipe 15 is arranged a pneumatically controlled valve.

In the system illustrated in Fig. 1 there are shown four return tubes 10, and consequently four exhaust tubes 14, and four controlling valves between said tubes 14, and four controlling valves between said tubes and the main suction pipe 15. Two of these valves 16 are pressure operated, the other two, 16^a, being operated by suction. The pressure operated valves consist of a sliding valve 17 connected to a valve rod 18 and normally held in closed position by a spring 19. The valve rod 18 is connected to a diaphragm 20. The interior of the diaphragm chamber is in communication with a small pipe 22. The valves 16^a which are operated by suction are constructed exactly as the pressure valves, except that the position of the diaphragm in the diaphragm chamber is reversed, as shown in Figs. 4 and 5, the diaphragm chamber being in communication with the small pipe 23. One of the pipes 22 and one of the pipes 23 are connected to a valve operating pipe 24, the other pipes 22 and 23 being connected to a similar operating pipe 25. These pipes 24 and 25 lead to a pneumatic switch device 26. This switch device consists of two pneumatic switch arms 27 and 28, each of said arms being formed with a hollow hub 29 in communication with one of the pipes 24 or 25. Connected to this hollow hub is a tubular arm 30 which at its free end is formed with two openings 31 and 31^a. The switch device 26 is provided with two channels 32 and 33. Ports 34 and 35 are formed in the device 26 and open into the channel 32 while ports 36 and 37 open into the channel 33. In Fig. 2 of the drawings the switch arm 27 is in position to bring its port 31 into register with the port 37 of the channel 33 while the port 31^a of said switch arm is out of register with the port 35 of channel 32. The channel 32 is connected by a pipe 38 with the main suction pipe 15, and the channel 33 is connected by a pipe 39 with the pressure pipe 1. It is, therefore, clear that when the motor is in operation air will be sucked from the pipe 38 and channel 32, and will be forced into pipe 39 and channel 33. In the position of the switch arm 27 shown in Fig. 2 air will be forced through the pipe 39, channel 33, port 37 and registering port 31 of the switch arm, thence through the switch arm and its hub into pipe 24. From pipe 24 air will pass into the pipes 22 and 23 connected therewith, and thence into the diaphragm chambers. As one of the diaphragm chambers is connected with a pressure operated valve and the other

with a vacuum or suction valve, only the pressure valve will be operated. It is, therefore, clear that the valve 16 will be operated when air under pressure is admitted to pipe 24, thereby opening the connected pipe 14 to the main suction pipe 15 so that air will be drawn through one of the outgoing tubes. When either of the switch arms 27 and 28 is shifted to bring its port 31^a over either the port 34 or port 35 air will be drawn from the connected pipe 24 or 25 through the pipe 38. The result of this is that the suction valve connected to said pipe 24 or 25 will be operated, thereby opening the valve 16^a and placing the connected pipe 14 into communication with the main suction pipe 15.

In order to operate the pneumatic switch arms 27 and 28 I provide rotatable switch operating devices 40 and 41, said devices being mounted on a shaft 42 driven through a worm gear 43 which receives its motion from a worm 44 on the shaft of the motor 45. Each pneumatic switch arm is provided with an operating finger 46 which projects into the path of cams 47 and 48 on the switch operating disks 40 and 41. The cams 47 are lower than the cams 48, and the cams on one disk are arranged perpendicularly to the cams on the other disk, and the cams on each disk are arranged at diametrically opposite points. By this means said cams will operate alternately, that is to say, when cam 47 of disk 40 is in engagement with the operating finger 46 of switch 27 the cams of disk 41 will be out of contact with the finger 46 of the switch 28. By this means only one valve 16 or 16^a will be operated at any one time so that only one return tube will be connected to the main exhaust tube 15 at any one time. It is also clear that during one revolution of the shaft 42 all of the return tubes will be connected in succession to the main exhaust tube 15, this operation being repeated for each revolution of the shaft 42 as long as the motor remains in operation. One great advantage of this arrangement is that carriers may be dropped into the receiving ends of the return tubes as fast as may be desired, said carriers being drawn through the tubes when the proper valve is operated to connect the main exhaust tube to the return tube in which carriers have been placed. This forms a very convenient and efficient arrangement and permits the central office operator to handle a great many carriers and to distribute them in a great many return tubes. There are no doors to be opened or closed; there is no switch device of any kind to be operated, the clerk or attendant giving his entire time to the business of handling the carriers and their contents, and placing the carriers in the open ends of the return tubes for their return to their proper outlying stations. Each switch arm is formed with suit-

able slides 49 which are adapted to cover the ports 34, 35, 36 and 37 when said ports are not in register with the ports in the switch arms.

5 The motor is connected by a belt 50 with the operating shaft of the blower 3. It will, of course, be understood that any form of blower may be used, and that it may be connected in any suitable manner with the motor. It will also be understood that any number of switch arms 27 and 28 may be employed, the switch operating mechanism being modified to operate said arms in succession, and while I have shown only two of 10 said arms operating four valves, I do not wish to be limited in this respect.

I have found that an apparatus constructed as described is so economical in the use of electric power and operates with such a low 15 air pressure in the tubes that the motor and blower may be operated at a low cost in installations where the use is quite constant during the working hours. In installations where it is probable that the use of the apparatus will be, to a certain extent, intermittent I provide, in order to effect a saving in the expenditure of electric power, an automatic motor starting and stopping means adapted to be operated from each of the receiving terminals in the transmission tube, and also from each of the receiving terminals at the central station or cashier's desk. To this end I provide at the receiving terminals 4 a pair of contacts 51 which are 20 adapted to close a battery circuit through an electro-magnet 52. These contacts are adapted to be brought into engagement by means of a cam 53 carried by the terminal door 5, as shown in Fig. 8. It will thus be seen that when any one of the doors of the terminals 4 is opened the magnet circuit will 25 be completed through the adjoining contacts. Adjacent each of the receiving terminals 10 at the central station is mounted a pair of contacts 54 which are adapted to 30 be brought into engagement with each other by means of an arm 55 connected to a pivoted trigger 56 which projects into the receiving terminals 10 and normally lies in the path of the inserted carrier. It will thus 35 be seen that when a carrier is placed in any one of the receiving terminals 10 to be transmitted to an outlying station the magnet circuit will be completed through the adjoining 40 pair of contacts.

In a convenient position near the motor is arranged a pneumatically operated motor controlling apparatus. This controlling apparatus consists of a main diaphragm chamber 57 in which is arranged a main diaphragm 58. Connected to this chamber is an air exhaust pipe 59, said pipe being connected to the exhaust tube 15. It will, of course, be understood that the diaphragm 60 chamber 57 is to be located in a convenient

position with respect to the motor in order that the air will be properly and promptly exhausted from said chamber. The chamber 57 is provided with an inlet valve 60 which is connected to and operated by lever 61. 70 On this lever is secured an armature which is adapted to be attracted by the electro-magnet 52, so that when the magnet circuit is completed the lever 61 will be swung on its pivot to open the inlet valve 60 of the diaphragm chamber, and thereby destroy the 75 vacuum therein.

A pair of contacts 62 is arranged close to the end of the lever 61, one of said contacts being adapted to be engaged by the said lever, when the inlet valve 60 is opened, to close the circuit through a suitable motor starting solenoid 63. When said solenoid circuit is closed the motor circuit is closed through contacts 64 and the motor will continue to drive the blower until the solenoid circuit is interrupted. Connected to the main diaphragm 58 is a pin 65 which normally engages a pair of contacts 66 arranged in a second solenoid circuit. In said second solenoid circuit is arranged a pair of contacts 67 which are adapted to be brought together by the core 68 of the solenoid when 80 said core is moved by the solenoid coil.

The operation of the motor controlling 85 means may be briefly described as follows: When any one of the terminal doors 5 is opened the electro-magnet circuit is closed and the said magnet energized thereby moving the lever 61 to open the valve 60 of the 100 main diaphragm chamber. The movement of this lever closes the solenoid circuit through the contacts 62, thereby completing the motor circuit through contacts 64 and starting the blower to draw air 105 through the suction pipe 15 and to force it through the delivery tube 1. When the valve 60 is opened the diaphragm 58 will move inwardly under the influence of the spring 65^a, thereby bringing the contacts 110 66 into engagement to close the second solenoid circuit. By this means the motor circuit will be held closed through the contacts 67 and 66 and the contacts 62 may separate without affecting the solenoid circuit. 115 The motor will now continue to operate until a sufficient degree of vacuum has been produced in the main diaphragm chamber through the pipe 59 to return the diaphragm 58 to its normal position and thereby separate contacts 66. As soon as said contacts are separated the solenoid circuit is interrupted and the motor circuit broken at the contacts 64. It will, of course, be understood 120 that the same cycle of operations takes place 125 when a carrier is inserted in any one of the receiving terminals 10, the electro-magnet circuit being then completed through one of the pairs of contacts 54. After the carrier has passed into the transmission tube 130

through the terminal 10, or the door 5 has been closed, the contacts 54, or the contacts 51, will separate, thereby deenergizing the electro-magnet and permitting the valve 60 to close. Vacuum will then be produced in the diaphragm chamber through the pipe 59, as previously described, and the length of time required to develop the proper degree of vacuum may be regulated by a suitable 5 valve 59^a arranged in the pipe 59. This type of motor controlling apparatus is disclosed in my pending application, Serial No, 495,127, filed May 10, 1909.

Having thus fully described my invention, 15 what I claim as new and desire to secure by Letters Patent is:

1. A pneumatic despatch tube apparatus comprising a transmission tube leading to a central station, a plurality of receiving 20 terminals in said tube each of said terminals being located at an outlying station, a series of return tubes from said central station to said outlying stations, a blower, means connecting the pressure side of said blower to the outer end of the single transmission tube leading to the central station, means operating to automatically connect and disconnect the outer ends of the return tubes in succession to the suction side of the blower, 25 and means for operating said blower.

2. A pneumatic despatch tube apparatus comprising a single transmission tube leading to a central station, a plurality of receiving terminals in said tube, each of said 35 terminals being located at an outlying station, a series of return tubes leading from the central station to said outlying stations, said return tubes being open at their central station ends, a blower, means connecting the pressure side of said blower to the outer end of the single transmission tube, a suction tube connected to the suction side of said blower, and means operating automatically to open and close communication 40 between said suction tube and the outlying ends of the return tubes.

3. A pneumatic despatch tube apparatus comprising a single transmission tube leading to a central station, a plurality of receiving 50 terminals in said tube, each of said terminals being located at an outlying station, a series of return tubes leading from the central station to the said outlying stations, a blower, an exhaust tube connected to the suction side of the blower, means connecting the pressure side of the blower to the single transmission tube, and means for successively placing the outer ends of the return tubes in communication with the suction tube.

4. A pneumatic despatch tube apparatus comprising a single transmission tube leading to a central station, a plurality of receiving terminals in said tube, each of said 65 terminals being located at an outlying sta-

tion, a series of return tubes leading from the central station to the said outlying stations, a blower, an exhaust tube connected to the suction side of the blower, means connecting the pressure side of the blower to the single transmission tube, a motor, and means operated by the motor for successively placing the outer ends of the return tubes in communication with the suction tube.

5. A pneumatic despatch tube apparatus 70 comprising a single transmission tube, a plurality of terminals in said tube, each of said terminals being located at an outlying station, a series of return tubes, a blower, means connecting the pressure side of the blower to the single transmission tube, a suction tube connected to the suction side of the blower, valves controlling communication between the suction pipe and the outer ends of the return tubes, and means for successively operating said valves to place said return tubes in communication with the suction pipe.

6. A pneumatic despatch tube apparatus 75 comprising a single transmission tube, a plurality of terminals in said tube, a series of return tubes, a blower, means connecting the pressure side of the blower to the single transmission tube, a suction tube connected to the suction side of the blower, pneumatically operated valves controlling communication between the suction pipe and the outer ends of the return tubes, and means for successively operating said valves to place said return tubes in communication 80 with the suction pipe.

7. A pneumatic despatch tube apparatus comprising a single transmission tube, a plurality of terminals in said tube, a series of return tubes, a motor, a blower, means connecting the pressure side of the blower to the single transmission tube, a suction tube connected to the suction side of the blower, valves controlling communication between the suction pipe and the outer ends of the return tubes, and means operated by the motor for successively operating said valves to place said return tubes in communication 95 with the suction pipe.

8. A pneumatic despatch tube apparatus 100 comprising a single transmission tube, a plurality of terminals in said tube, a series of return tubes, a blower, means connecting the pressure side of the blower to the single transmission tube, a suction tube connected to the suction side of the blower, a motor for operating the blower, pneumatically operated valves controlling communication between the suction pipe and the outer ends of the return tubes, and means operated by the 105 motor for actuating said valves.

9. A pneumatic despatch tube apparatus 110 comprising a single transmission tube, a plurality of receiving terminals therein, a plurality of return tubes, a blower, a motor 115

for operating said blower, a suction tube connected to the suction side of the blower, means connecting the outer end of the transmission tube to the pressure side of the blower, a pneumatically operated valve controlling communication between the outer end of each of the return tubes, and the suction tube, some of said valves being pressure operated and the others being adapted to 5 be opened by suction, and means operated by the motor for controlling the flow of air to and from said valves.

10. A pneumatic despatch tube apparatus comprising a single transmission tube, a plurality of terminals in said tube, a series of return tubes, a suction tube, a blower, means connecting the pressure side of the blower to the single transmission tube, means connecting the suction tube to the suction 15 side of the blower, a pneumatically operated valve controlling communication between the outlying end of each of the return tubes and of the suction tube, some of said valves being operated by suction, and others by 20 pressure, and means for connecting the pressure and suction sides of the blower to said valve.

11. A pneumatic despatch tube apparatus comprising a single transmission tube, a plurality of terminals in said tube, a series 30 of return tubes, a suction tube, a blower, means connecting the pressure side of the blower to the single transmission tube, means connecting the suction tube to the suction 35 side of the blower, a pneumatically operated valve controlling communication between the outlying end of each of the return tubes and of the suction tube, some of said valves being operated by suction, and others by 40 pressure, a valve operating pipe connected to one suction valve and one pressure valve, and means for alternately connecting said pipe to the pressure side and to the suction side of the blower.

45. 12. A pneumatic despatch tube apparatus comprising a single transmission tube, a plurality of terminals in said tube, a series of return tubes, a suction tube, a motor, a blower, means connecting the pressure side 50 of the blower to the single transmission tube, means connecting the suction tube to the suction side of the blower, a pneumatically operated valve controlling communication between the outlying end of each of the return 55 tubes and of the suction tube, some of said valves being operated by suction, and others by pressure, a valve operating pipe connected to one suction valve and one pressure valve, and means operated by the motor 60 for alternately connecting said pipe to the pressure side and the suction side of the blower.

65. 13. A pneumatic despatch tube apparatus comprising a single transmission tube, a series 65 of terminals in said tube, a series

of return tubes, a suction tube, a motor, a blower, means connecting the pressure side of the blower to the single transmission tube, means connecting the suction tube to the suction side of the blower, a pneumatically 70 operated valve controlling communication between the outlying end of each of the return tubes and of the suction tube, some of said valves being operated by suction and others by pressure, a valve operating pipe 75 connected to one suction valve and one pressure valve, a pneumatic switch adapted to place said pipe alternately in communication with the pressure side and the suction side of the blower, and means actuated by 80 the motor for operating said pneumatic switch.

14. A pneumatic despatch tube apparatus comprising a single transmission tube, a plurality of terminals in said tube, a series 85 of return tubes, a blower, a motor for operating said blower, a suction pipe connected to the suction side of the blower, the pressure side of said blower being connected to the single transmission tube, a pneumatically 90 operated valve controlling communication between the outer end of each of the return tubes and the suction tube, some of said valves being operated by suction and the others by pressure, a series of valve actuating pipes, each of said pipes being in communication with one pressure actuated valve, a suction valve, a pneumatic switch for each of the valve actuating pipes, and means actuated by the motor for operating 95 said switches to alternately connect each of the valve operating pipes to the pressure side and to the suction side of the blower.

15. A pneumatic despatch tube apparatus comprising a transmission tube leading to a central station, a plurality of receiving terminals in said tube, a series of return tubes from said central station to outlying stations, a blower, means connecting the pressure side of said blower to the single 100 transmission tube leading to the central station, means connecting the outer ends of the return tubes to the suction side of the blower, a motor for operating said blower, and a timing means to permit said motor to 105 operate a predetermined time.

16. A pneumatic despatch tube apparatus, comprising a transmission tube leading to a central station, a plurality of receiving terminals in said tube, a series of return tubes from said central station to outlying stations, a blower, means connecting the pressure side of said blower to the single 110 transmission tube leading to the central station, means connecting the outer ends of the return tubes to the suction side of the blower, a motor for operating said blower, means at each receiving terminal for starting said motor, and means for stopping said motor after a predetermined time. 115

17. A pneumatic despatch tube apparatus comprising a transmission tube leading to a central station, a plurality of receiving terminals in said tube, a series of return tubes from said central station to outlying stations, a blower, means connecting the pressure side of said blower to the single transmission tube leading to the central station, means for intermittently connecting 10 the outer ends of the return tubes to the suction side of the blower, means for operating said blower, and means for stopping said blower after all of the return tubes have been connected to the suction side of the 15 blower.

18. A pneumatic despatch tube apparatus comprising a single transmission tube, a plurality of terminals therein, a series of return tubes, a suction tube, a blower, a 20 motor for operating said blower, means connecting the outer end of the transmission tube to the pressure side of the blower and the suction tube to the suction side of the blower, a valve for controlling communication 25 between the outer end of each return tube and the suction tube, means actuated by the motor for operating said valves in succession, means at each receiving terminal for starting the motor, and means for 30 stopping the motor after all of the said valves have been operated.

19. A pneumatic despatch tube apparatus comprising a single transmission tube, a plurality of terminals in said tube, a series 35 of return tubes, a blower, a motor for operating said blower, a suction pipe connected to the suction side of the blower, the pressure side of said blower being connected to the single transmission tube, a pneumatically 40 operated valve controlling communication between the outer end of each of the return tubes and the suction tube, some of said valves being operated by suction and the others by pressure, a series of valve actuating pipes, each of said pipes being in communication with one pressure actuated valve and one suction valve, a pneumatic switch for each of the valve actuating pipes, means actuated by the motor for operating said 45 switches to alternately connect each of the valve operating pipes to the pressure side and to the suction side of the blower, means at each receiving terminal for starting the motor, and means for stopping the motor 55 when all of the valves have been operated.

20. A pneumatic despatch tube apparatus comprising a single transmission tube, a plurality of terminals in said tube, a series 60 of return tubes, a suction tube, a blower, means connecting the pressure side of the blower to the single transmission tube, means connecting the suction tube to the suction side of the blower, pneumatically operated valves controlling communication

between the outlying ends of the return tubes and the suction tube, some of said valves being operated by suction and others by pressure, a valve operating pipe connected to one suction valve and one pressure valve, and means for alternately connecting 70 said pipe to the pressure side and to the suction side of the blower, and a timing means for said motor.

21. A pneumatic despatch tube apparatus comprising a single transmission tube, a 75 plurality of terminals in said tube, a blower, means connecting the pressure side of said blower to said single transmission tube, a series of return tubes, a suction tube connected to the suction side of the blower, a 80 valve controlling communication between the outer end of each return tube and the suction tube, means for operating said valves in succession whereby the outer ends of the return tubes will be in succession in 85 communication with the suction tube, and a pneumatically operated timing means for said motor.

22. A pneumatic despatch tube apparatus comprising a series of tubes, a blower, a 90 motor for operating said blower, means operated by the motor for successively connecting the suction side of the blower to the ends of said tubes.

23. A pneumatic despatch tube apparatus 95 comprising a series of tubes, a blower, a motor for operating said blower, means operated by the motor for successively connecting the suction side of the blower to the ends of said tubes, and a timing means for 100 the motor.

24. A pneumatic despatch tube apparatus comprising a series of tubes, a blower, a motor for operating said blower, means operated by the motor for successively connecting the suction side of the blower to the ends of said tubes, and a pneumatically operated timing means for said motor.

25. A pneumatic despatch tube apparatus comprising a series of tubes, a blower, a motor for operating said blower, means operated by the motor for successively connecting the suction side of the blower to the ends of said tubes, and a timing means to stop said motor when all of the outlying 115 ends of the return tubes have been in succession connected to the exhaust side of the motor.

26. A pneumatic despatch tube apparatus comprising a transmission tube leading to a central station, a plurality of receiving terminals in said tube, a series of return tubes from said central station to outlying stations, a blower, means for connecting the pressure side of said blower to the outer end 120 of the single transmission tube, automatically operating means connecting the outer ends of the return tubes in succession to the

suction side of the blower, a motor for operating said blower and a timing means for the motor.

27. A pneumatic despatch tube apparatus comprising a series of tubes, a blower, a motor for operating said blower, means for successively connecting the suction side of the blower to the ends of said tubes and a timing means for the motor.

10 28. A pneumatic despatch tube apparatus comprising a single transmission tube, a blower, means connecting the pressure side of said single transmission tube, a series of return tubes, a blower operating mechanism, 15 means to place the suction side of the blower in communication with the return tubes in succession, and means to stop the blower operating mechanism after all of said return tubes have been connected to the suction 20 side of the blower.

29. A pneumatic despatch tube apparatus comprising a series of tubes, a blower, a motor for operating said blower, means for successively connecting the suction side of the blower to the tubes and means to stop the motor after all of said tubes have been connected to the blower.

30. A pneumatic despatch tube apparatus comprising a single transmission tube, a plurality of terminals in said tube, a series of return tubes, a blower, means connecting one side of said blower to the single transmission tube, means for connecting the other side of said blower to the ends of the return tubes 35 in succession, a blower operating mechanism, and means for stopping the blower operating mechanism after all of said return tubes have been connected to the blower.

31. A pneumatic despatch tube apparatus comprising a single transmission tube, a plurality of terminals in said tube, a blower, means for connecting one side of said blower to said single transmission tube, a series of return tubes, a blower operating mechanism 45 and means operated from said blower operating mechanism to control communication between the other side of the blower and the return tubes.

32. A pneumatic despatch tube apparatus comprising a single transmission tube extending from a central station to an outer station, a plurality of terminals in said tube between its outer end and the central sta-

tion, a blower, the pressure side of the blower being connected to the outer end of the single transmission tube, a series of return tubes extending from the central station to the outlying stations, a blower operating mechanism and means operating to connect the suction side of the blower to and disconnect it from the outer ends of the return tubes in succession.

33. A pneumatic despatch tube apparatus comprising a single transmission tube extending from a central station to an outer station, a plurality of terminals in said tube between its outer end and the central station, a blower, the pressure side of the blower being connected to the outer end of the single transmission tube, a series of return tubes extending from the central station to the outlying stations, a blower operating mechanism, means operating to connect the suction side of the blower to and disconnect it from the outer ends of the return tubes in succession, a timing means for the blower operating mechanism, and means operating upon the insertion of a carrier to start the timing means.

34. A pneumatic despatch tube apparatus comprising a series of return tubes extending from a central station to outlying stations, a blower, a motor for operating said blower and means for successively connecting and disconnecting the suction side of the blower to and from the outlying ends of said return tubes in succession.

35. A pneumatic despatch tube apparatus comprising a series of return tubes extending from a central station to outlying stations, a blower, a motor for operating said blower, means for successively connecting and disconnecting the suction side of the blower to and from the outlying ends of said return tubes in succession, and means for stopping the motor after all of said return tubes have been connected to and disconnected from the blower.

In testimony whereof I hereunto affix my signature in the presence of two witnesses 100 this 23rd day of June 1910.

JOHN T. NEEDHAM.

Witnesses:

F. R. MILLER,
WM. R. DAVIS.
